UNITED STATES PATENT OFFICE

EDWARD C. ALBRIGHT, OF CONNERSVILLE, INDIANA, ASSIGNOR TO INDIANA LAMP CORPORATION, OF CONNERSVILLE, INDIANA, A CORPORATION

LAMP STRUCTURE

Application filed March 14, 1930. Serial No. 435,722.

This invention relates to a combination lamp provided with an illuminated name plate designation.

The chief object of this invention is to provide a name plate construction in a combination lamp which is so arranged that it is illuminable by the lamp bulb therein and forms the legend by reflection.

One feature of the invention consists in the interior or enclosed type of name plate or legend device.

Another feature of the invention consists in the embodiment of the invention in a multiple compartment lamp wherein each lamp bulb therein is arranged to illuminate the legend device.

The full nature of the invention will be understood from the accompanying drawings and the following description and claims:

20 In the drawings, Fig. 1 is a central sectional view of a combination stop and tail lamp in which the invention is embodied.

Fig. 2 is a front elevational view thereof.

Fig. 3 is a central sectional view of a tail lamp embodying the invention.

Fig. 4 is a similar view of a so-called side or parking lamp.

In the drawings, 10 indicates a bowl type casing provided with a reinforcing back plate 11 supporting any desired type of anchorage 12.

Also supported thereby may be the license plate bracket 13. The plate 11 and casing are apertured and a plug receiving socket type construction 14 is supported thereby.

35 Extending forwardly and upwardly is a lamp bulb receiving socket 15 and extending downwardly and forwardly is a lamp bulb receiving socket 16. These sockets are supported by the straps 17 and 18 secured to the casing or may be otherwise supported in the afore-

40 said relationship, to wit, in diverging relation in the upper and lower portions of the casing. A partition 19 may be provided if desired. The casing is apertured as at 20 to receive a clear glass closure 21 having the flange 22 for retaining the same in the casing. This permits the light rays from lamp bulb

45 24 mounted in socket 16, to illuminate a license plate carried by bracket 13. A larger lamp

bulb 23 is receivable by socket 15 for stop light purposes.

The rim 25 includes a peripheral angularly directed flange 26 which engages the in-turned flange 27 upon the forward edge of the casing. A forwardly directed peripheral flange 28 constitutes an extension of the inward flange 27 and the aforesaid constitutes a seat for the rear portion of the rim. The rim includes an upper aperture 29, an intermediate aperture 30 and a lower aperture 31, said apertures being defined by strap portions 32 and 33, which extend from one side of the rim to the opposite side as illustrated in Fig. 2.

55 Mounted in the aperture 29 is a stop light designating lens or closure 34 which preferably is provided with a ruby field and the letters are impressed therein and are indicated at 35, being preferably of amber color. The light bulb 23 when energized, is adapted to illuminate the legend for warning purposes. The tail light aperture 31 supports a lens or closure 36, which is illuminated, as well as insert 21, when the tail light bulb 24 60 is energized.

65 The intermediate aperture 30 is closed by a clear glass or lens which may be of the plain or magnifying type, and the same is indicated by the numeral 36. A lens or closure retaining plate 37 having a peripheral flange 38 is adapted to bear against the forward end of the peripheral flange 28. The plate is apertured at its top portion as at 39 and an angle bracket or clip 40, carrying a locking pin 41, or the like, is arranged to seat in the socket 42, formed in the flange 28 for locking the closure to the rim and it to the casing. The clip 40 is suitably secured to the rim. The closure retaining plate 37 is apertured at 43 70 and said aperture is in full registration with aperture 29. Similarly, the plate is apertured at its lower portion as at 44 and the aperture 44 is in full registration with the stop light aperture 31. The central intermediate aperture 45 is in full registration with the central intermediate aperture 30 in the door rim.

75 90 95 100 The casing supports a nut 46 and said nut is threaded to receive a locking bolt 47, the

latter extending through the aperture 48 in the flange 28 of the casing. The opening through the door rim that receives said bolt is countersunk as at 49. Through the pin 5 and socket connection 41-42 and the bolt and nut connection 47-48, the door rim is detachably anchored to the casing. As shown clearly in Fig. 1 the exposed face of the glass lens or closure is preferably flat so they may be readily cleaned by wiping.

In Fig. 1 of the drawings, there is illustrated a plate 50 which extends substantially across the casing and is provided with two forwardly projecting portions 51 at its upper and lower edges, which terminate immediately adjacent the plate 37 and bear upon said plate 37 by means of the outwardly directed flanges 52. The opposite sides of this U-shaped container or chamber forming member are suitably apertured and provided with either a series of circular apertures or an equivalent single elongated aperture, as at 53. Suitably supported adjacent the back 40 is a name plate or legend forming member 54. This may be press fitted into the U-shaped member or may be otherwise secured thereto. Light from bulb 23 or 24 or both, passes through aperture 51 and a part at least is reflected onto the legend forming member 54 to illuminate the face thereof and these rays are then reflected through the clear glass closure 36 for indicating the desired legending, such as the name of the automobile or the like.

The U-shaped legend supporting member may be secured either to the plate 37 and carried thereby or may be secured to the partition 19 and carried thereby. Either method is available but the former is preferred because it permits of the formation of the U-shaped container integral with the retaining plate 37.

In either event, whether the U-shaped plate legend retainer is formed integral with plate 37 or is suitably secured thereto by spot-welding or the like, the ends may be left open and in this way when the door is removed, the container is exposed so that the name plate may be readily removed for cleaning or in initial assembling, may be readily assembled. Of course if the U-shaped plate is supported by the partition, the name plate when the door rim is removed, has its face exposed and can of course, be readily cleaned in that manner as well as readily installed and removed. The particular method of mounting the U-shaped name plate retainer may, therefore, be of either form and whichever member, to wit, plate 37 or partition 19, supports the same, the U-shaped retainer should be arranged to bear against the other, except in the case where the U-shaped retainer is secured to the plate and in turn supports the partition 19, so that the plate 37, the U-shaped retainer and the partition 19 in this latter

event are all removable as a unit, when the door rim is removed.

In Fig. 3 there is illustrated a combination stop and tail lamp wherein but a single multi-filament bulb is employed.

In this form of the invention 110 indicates the casing having the rim receiving flange 127 which receives the rim 125 that mounts in an opening 131 the closure 135. The transverse portion 133 separates closure 135 from the closure 136. Positioned in spaced relation to closure 136 is the support 150, the face 154 of which includes suitable legend forming means, the same being arranged to have illumination impinge thereon and be reflected thereon from the back of the closure 136 by passing through the open end 151 of the legend forming construction, illumination being obtainable from the light bulb 124 having multi-filaments and the axis of the light bulb being inclined to the axis of the conoidal casing 110. Casing 110 is provided with the opening 120 which receives the closure 121 whereby the bulb 124 is arranged to illuminate the license plate.

In Fig. 4 the modified form of the invention is illustrated and this form embodies a so-called side or cowl lamp construction or lamps of a similar character. 210 indicates the conoidal casing, 215 the light bulb socket inclined at an angle to the axis of the conoidal casing and mounting light bulb 223 which illuminates by direct illumination the portion of the closure 235 immediately in front of the same, said closure 235 being mounted in and upon the rim 225 supported upon the seat 227 of the casing. The closure is retained by suitable means 238.

Supported in spaced relation to the casing is the legend forming means including the inclined plate portion 250, through the opening 251 of which light from the bulb 223 at least partly engages the closure 235 and is reflected upon the legend forming face 254 to form the legend by reflection therefrom and through the closure 235.

The invention claimed is:

1. In a combination multiple purpose lamp, an open ended casing, a rim having a flange, closure means for said open end including lens means in said rim and an apertured plate in said rim, a lamp bulb in said casing opposite one portion of said lens means, and means for supporting a legend on said plate spaced from and back of another portion of said lens means and adjacent thereto in position to be illuminated by said lamp bulb at least partly by reflection from the back of said lens.

2. In a combination multiple purpose lamp, an open ended casing, a rim having a flange, closure means for said open end including lens means in said rim and an apertured plate in said rim, a lamp bulb in said casing opposite one portion of said lens means, means for supporting a legend on said plate spaced from

and back of another portion of said lens means and adjacent thereto in position to be illuminated by said lamp bulb at least partly by reflection from the back of said lens, another lamp in said casing opposite another portion of said lens means, light from said second mentioned lamp being at least partly reflectable from the back of said lens on to the legend, and a partition within the casing separating the same into individual lamp compartments.

3. In a combination multiple purpose lamp, an open ended casing, a rim having a flange, closure means for said open end including lens means in said rim and an apertured plate in said rim, a lamp bulb in said casing opposite one portion of said lens means, means for supporting a legend on said plate spaced from and back of another portion of said lens means and adjacent thereto in position to be illuminated by said lamp bulb at least partly by reflection from the back of said lens, another lamp in said casing opposite another portion of said lens means, light from said second mentioned lamp being at least partly reflectable from the back of said lens on to the legend, and a partition within the casing separating the same into individual lamp compartments, said partition being secured to the legend supporting means.

4. In a combination multiple purpose lamp, an open ended casing, a rim having a flange, closure means for said open end including lens means in said rim, a pair of lamp bulbs in said casing, opposite spaced portions of said lens means, a U-shaped legend support, the side walls of which are suitably apertured for permitting light from the lamp bulbs to pass therethrough in said rim, said U-shaped legend support having an intermediate portion spaced from and back of another portion of said lens means and adjacent thereto in position for the legend supported by the midportion of said U-shaped support to be illuminated at least partly by reflection from light from either bulb from the back of said lens.

5. In a combination multiple purpose lamp, an open ended casing, a rim having a flange, closure means for said open end including lens means in said rim, a pair of lamp bulbs in said casing opposite spaced portions of said lens means, a U-shaped legend support, the side walls of which are suitably apertured for permitting light from the lamp bulbs to pass therethrough in said rim, said U-shaped legend support having an intermediate portion spaced from and back of another portion of said lens means and adjacent thereto in position for the legend supported by the midportion of said U-shaped support to be illuminated at least partly by reflection from light from either bulb from the back of said

lens, and a partition within the casing separating the casing into individual lamp compartments.

In witness whereof, I have hereunto affixed my signature.

EDWARD C. ALBRIGHT.
